(57) **CLAIM**

The ornamental design for a vehicular embellishment, as shown and described.

DESCRIPTION

FIG. 1 is a top view of the vehicular embellishment of my design;

FIG. 2 is a front view thereof;

FIG. 3 is a rear view thereof;

FIG. 4 is a right side view thereof, the left side being a mirror image thereof;

FIG. 5 is a perspective view thereof, shown in one possible vehicular orientation;

FIG. 6 is a front view of FIG. 5;

FIG. 7 is a left side view of FIG. 5;

FIG. 8 is a right side view of FIG. 5; and,

FIG. 9 is a top view of FIG. 5.

In FIGS. 1–9, broken lines showing environment or structure are for illustrative purposes only and form no part of the claimed design.

The omission of a view indicates that the omitted view is plain and unornamented.
